L. H. MILES

SIREN AND ATTACHING MEANS THEREFOR

Filed May 13, 1925

FIG. 4

FIG. 2

FIG. 1

FIG. 3

INVENTOR.
LESTER H. MILES

BY *Lester H. Miles*,
ATTORNEY.

UNITED STATES PATENT OFFICE.

LESTER H. MILES, OF LOS ANGELES, CALIFORNIA.

SIREN AND ATTACHING MEANS THEREFOR.

Application filed May 13, 1925. Serial No. 29,891.

To all whom it may concern:

Be it known that I, LESTER H. MILES, a citizen of the United States, residing at Los Angeles, in the county of Los Angeles and 5 State of California, have invented a certain new and useful Improvement in Sirens and Attaching Means Therefor, of which the following is a full, clear, and exact description, reference being had to the accompanying 10 drawings.

This invention relates to sirens and attaching means therefor.

The general object of the invention is to provide an improved means for attaching 15 a siren to a gasoline engine in such manner that the siren may be effectively operated.

A further object of the invention is to provide an improved mounting for a siren whereby the latter can be driven from the 20 fan shaft of an engine.

Other objects of the invention will be apparent from the following description taken in connection with the accompanying drawings wherein Fig. 1 is a side elevation partly 25 in section showing my improved siren attaching means; Fig. 2 is a top plan view of the invention; Fig. 3 is a front end view of the siren and attaching means and Fig. 4 is a front elevation of the siren with the 30 cover removed.

Referring to the drawing by reference characters, I have shown an engine block at 10. A fan shaft is shown at 11. This fan shaft is provided at one end with a fan 12 having a hub 14 thereon which engages the fan shaft. A pulley 15 has end flanges 16 thereon, one of which is secured to the hub 14 in such manner that a belt passing over the pulley 15 will drive the fan.

Arranged upon the fan shaft 11 I show a driving disc 20. This disc is preferably made of suitable material such as vulcanite and it is apertured to receive bolts 21 which pass through and are secured to the central 45 portion of the pulley 15 as shown in Fig. 1.

Mounted upon the engine block 10, I show a bracket 25. This bracket is provided with apertures through which studs 26 extend and these studs receive nuts 27 for holding the bracket in place. The bracket 25 is provided with a boss 28 thereon through which a shaft 29 extends. This shaft is adjustable through said boss 28 and to hold it in adjustable position, I provide a set screw 30. Upon the 50 shaft 29 I arrange a siren 31. This siren 31

comprises a body part 32, a rotor 33 and a cover 34. The body part 32 is provided with a boss 35 thereon through which a drive shaft 36 extends. Adjacent the boss 35 I arrange an offset portion 38 which is apertured to receive the shaft 29. A cotter pin 40 is secured upon the lower end of the shaft 29 and this pin engages a washer 41 which in turn engages a spring 42. The spring 42 presses the siren upwardly into engagement with an adjustable collar 45 which is normally held in position by a set screw 46.

The set screw 46 on the collar 45 is adapted to engage a stud 48 arranged upon the offset portion 38. The construction is such that by 60 loosening the set screw 46 the collar 45 may be turned so that the head of the set screw 46 will engage the stud 48 to hold the parts against the action of a spring 50 which is connected to a plate 51 on the casing 32 at 65 one end and at the other end is secured to an eye bolt which is secured to the engine 10.

In order to swing the case 32 for a purpose to be presently described, I provide a coupling 53 including a ball and socket joint 70 54 which is connected by a rod 55 by an operating member (not shown) of any desired character.

The shaft 36 is shown as provided with ball races 60 at one end and at the other end 85 the shaft is extended and is threaded as at 61. Upon the threaded portion of the shaft, I adjustably mount a drive disc 62. This drive disc may be made of any desired material such as vulcanite and is adapted to be 90 held in place by lock nuts 63. By shifting the lock nuts longitudinally of the threaded portion 61 of the shaft 36 it will be apparent that desired adjustment of the drive disc 62 may be effected so that the driving mechanism may be used on engine assemblies of 95 widely different character.

In the operation of the device, the operator will pull the rod 55 so that the drive disc 62 is brought into engagement with the 100 driving disc 20 as shown in Fig. 2. When the use of the siren is no longer required the operator releases the rod 55 thus causing the spring 50 to swing the siren about the shaft 29 to remove the drive disc 62 from engagement with the driving disc 20. The studs 46 and 48 then engage to limit the action of 105 the spring 50.

Having thus described my invention, I claim:

In a device of the class described, an engine, a fan shaft mounted to rotate thereon, a fan on said fan shaft, said fan having a hub thereon, means to drive said fan, a driving disc arranged on said fan shaft and adapted to be driven thereby, a supporting member mounted on said engine, a siren mounted on said member, said siren comprising a body part having a rotor therein, a drive shaft for said rotor, said drive shaft projecting from said body, a drive disc on

said last mentioned shaft, and normally disposed adjacent said driving disc, means to swing said siren upon its shaft to hold said drive disc spaced from said driving disc and means acting against said holding means to rotate said siren on its shaft and to bring said drive disc to engagement with said first driving disc. 15

In testimony whereof, I hereunto affix 20 my signature.

LESTER H. MILES.
